COMBINATION DETACHABLE BRASSIERE,
GIRDLE, AND THE LIKE

Helen Harris, Staten Island, N. Y.

Application June 18, 1953, Serial No. 362,507

2 Claims. (Cl. 2—42)

This invention relates to new and useful improvements in undergarments for ladies and, more particularly, to such undergarments of the combined brassiere and girdle or garter belt or waistband type.

The invention has for its object the provision of a combination garment as mentioned which is characterized by an elastic waistband disposed between the brassiere and its associated girdle or garter belt for concealing and controlling the flesh of the wearer at the waistline.

A modification of the invention proposes the construction of a brassiere with a waistband for concealing and controlling the flesh of the wearer at the waistline.

Another object of the invention is to provide a combined brassiere, waistband and girdle with separable fastening means for detachably connecting the brassiere and waistband to the girdle.

Yet another object of the invention is to provide a combined brassiere, waistband and garter belt with separable fastening means for detachably connecting the waistband to the brassiere and garter belt.

A specific object of the invention is to provide an undergarment in the form of a brassiere with an elastic waistband for concealing and supporting the flesh of the wearer at the waistline, the waistband being stretchable in two different directions.

It is a further object of the present invention to form an undergarment of the class referred to which is easy to manufacture, which can be sold at a reasonable cost and which will be effective for its intended purposes in use.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a rear perspective view of a lady's undergarment embodying the features of the present invention, shown alone and in an open position.

Fig. 2 is a side elevational view thereof shown in operative use on the wearer.

Fig. 3 is a view similar to Fig. 2 but showing a modified form of the present invention.

Fig. 4 is a rear elevational view of a lady's undergarment embodying still another form of the present invention.

Fig. 5 is a front elevational view thereof.

Fig. 6 is a vertical sectional view taken on the plane of the line 6—6 of Fig. 5.

Fig. 7 is a vertical sectional view taken on the plane of the line 7—7 of Fig. 6.

Fig. 8 is a side elevational view of the waistband of Fig. 4.

Fig. 9 is a front elevational view of a combined bras-

2

siere and garter belt embodying still another form of the invention.

Fig. 10 is a rear elevational view thereof.

Referring now to Figs. 1—2, a combination lady's undergarment is illustrated which includes a brassiere 15 provided with a cloth bust-encircling section having heavy elastic body straps 16 stretchable in both directions, extending from the ends of said section and forming lateral extensions thereof, substantially as illustrated. Reinforcing strips 17 are provided at the adjacent free ends of straps 16, the strips 17 being provided with cooperating eyes 18 and loops 19 whereby to secure the brassiere 15 about the body, as shown in Fig. 2.

The brassiere 15 is open at the front, as at 20, and is provided with a pair of adjustable shoulder straps 21.

A pair of waistbands 22 of heavy elastic material stretchable in both directions are secured to the ends of body straps 16 beneath reinforcing strips 17 by stitching 23.

20 The free ends of waistbands 22 are provided with reinforcing strips 24 secured by stitching 25, the strips 24 being provided with cooperating eyes 26 and loops 27 whereby to secure the waistbands 22 about the waist, as shown in Fig. 2, said waistbands and the horizontal and vertical tension thereof serving to conceal and control the flesh of the wearer at the waistline. This construction permits a continuous open space 29 between the brassiere 15 and the top edges of bands 22 to permit breathing without discomfort.

25 30 A pair of spring clips 28 are secured to the bottom edges of body straps 16 adjacent the strips 17 at the rear of the brassiere, and serve to connect the construction with a girdle 30, avoiding bulges intermediate the bottom of bands 16 and the top of girdle 30. Thus, the bands 16 close the space between the brassiere 15 and girdle 30 around the entire circumference of the waist, serving thereby to conceal and control the flesh of the wearer at the waistline. Due to the construction, the bands 22 are connected to the brassiere only along strips

35 40 17, providing greater comfort and easier breathing. The bands 22 are also connected to the girdle 30 only by clips 28, for the same reason.

It will be noted that the above construction permits the brassiere 15 and bands 22 to be worn interchangeably with varying garter belts and girdles, not shown.

Referring now to Fig. 3, there is shown a modified form of the invention differing from the first form in the permanent attachment of the bands 22 to girdle 30 by means of stitching 31.

50 In other respects, the form of the invention shown in Fig. 3 is the same as that shown in Figs. 1 and 2, and like reference numerals identify like parts throughout the several views.

In the form of the invention illustrated in Figs. 4 to 8, 55 inclusive, a combination lady's undergarment is illustrated which comprises essentially a brassiere 15' and a girdle 16'. A salient feature of the present invention is the provision of a waistband 17' between the brassiere 15' and the girdle 16' at the rear and sides of the garment.

60 The waistband is formed of heavy elastic material and is set on the bias so that it stretches horizontally and vertically. This waistband extends around the back and sides of the garment and is connected permanently to the bottom edge of the brassiere 15' by a row of stitching 18'. The waistband is detachably connected to the girdle 16' at the rear and sides thereof by separable fastening elements 19' carried by tapes 19^a sewed along the adjacent meeting edges of the waistband and girdle.

65 70 The fastening elements are actuated by a slideable finger piece 20'. The brassiere 15' opens at the front as indicated at

Fig. 9 is a front elevational view of a combined bras-

21' and is provided with the conventional pair of shoulder straps 22'.

The waistband 17' closes the space between the brassiere 15' and girdle 16' at the rear and sides of the garment and serves to conceal and control the flesh of the wearer at the waistline. This construction permits a space 23' at the front of the garment between the brassiere and the girdle to permit breathing without discomfort.

It will be understood, of course, that the waistband 17' may be detachably connected to the brassiere 15' by separable fastening elements such as the elements 19' if desired.

In Figs. 9 and 10, a waistband 17", similar in construction to the waistband 17', is shown detachably connected to the rear and side portions of a conventional brassiere 15" and a conventional garter belt 24" for supporting hose supports 25". In this form of the invention, the bottom and side edges of the brassiere 15" have a plurality of spaced snap fastener socket elements 26" and the waistband 17" has a plurality of snap fastener stud elements 27" for coating with the socket elements 26" for detachably fastening the waistband to the brassiere. The waistband is similarly detachably connected to the garter belt by snap fastener socket elements 28" and snap fastener stud elements 29" on the adjacent meeting edges of the waistband and garter belt, respectively. The waistband serves to conceal and control the flesh of the wearer between the brassiere and garter belt at the waistline.

In other respects this form of the invention is similar to that shown in Figs. 4-8 and like reference numerals identify like parts in each of the several views.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as 40 new, and desire to secure by United States Letters Patent is:

1. In a brassiere, a bust-encircling section, a pair of body straps extending from the ends of said section forming lateral extensions thereof, adapted to come together 45 at the back of the wearer, releasable means for securing the free ends of said body straps together, a pair of

waistbands in overlapping relation to said body straps, said waistbands each being secured at one of its ends to the free end of the adjacent body strap, said waistbands being adapted to come together at the front of the wearer and spaced below the bust-encircling section, second releasable means for securing the free ends of said waistbands together, and releasable fastening means carried by said body straps near said first releasable means for connecting said body straps to a girdle or the like, said straps and waistbands being formed of heavy elastic material stretchable in two directions at substantially right angles to each other, said first releasable means including a pair of reinforcing strips secured to the free ends of said body straps with said waistband free ends therebetween, and cooperating fastening means carried by each of said strips, said second releasable means including a second pair of reinforcing strips secured to the free ends of said waistbands, and cooperating fastening means carried by each of said reinforcing strips.

2. A brassiere comprising a cloth bust-encircling section, elastic body straps secured to the ends of said section and forming lateral extensions thereof, fastening elements on the ends of said straps for securing the section to the body of the wearer, a pair of adjustable shoulder straps secured to the top edge of the bust-encircling section and to the elastic body straps remote from their free ends, a pair of elastic waistbands each having one of its ends secured to the free end of the adjacent elastic body strap, said waistbands being adapted to be turned back upon the body straps at the rear thereof, fastening elements on the free ends of said waistbands for connecting the bands at the front of the body of the wearer, below the bust encircling section, and clips depending from the shoulder straps remote 35 from their free ends for removably fastening the brassiere to a girdle.
